UNITED STATES PATENT OFFICE.

JOSEPH NELSON BENNOR, OF MACON, GEORGIA, ASSIGNOR TO THE BIBB MANUFACTURING COMPANY, OF SAME PLACE.

THREAD-FEEDING MECHANISM FOR STRAIGHT-KNITTING MACHINES.

SPECIFICATION forming part of Letters Patent No. 655,046, dated July 31, 1900.

Application filed January 30, 1899. Serial No. 703,761. (No model.)

To all whom it may concern:

Be it known that I, JOSEPH NELSON BENNOR, a citizen of the United States, residing at Macon, in the county of Bibb and State of Georgia, have invented certain new and useful Improvements in Thread-Feeding Mechanism for Straight-Knitting Machines, of which the following is a specification, reference being had therein to the accompanying drawings.

This invention is an improvement on the yarn-feeding mechanism for straight-knitting machines set out in Letters Patent of the United States to William Esty, No. 386,117, dated July 17, 1888, to which reference may be had, my aim being to provide a novel construction and organization of mechanism whereby two independent yarn-feeding devices substantially of the character shown in said patent may be effectively operated upon the machine with the view of supplying to the needles at predetermined intervals yarns of different size or color, as desired. Thus, for example, in the production of stockings the yarn used in the heel and toe portions may be of different color or different thickness from that used in the foot and leg portions thereof.

The precise character and scope of the invention will appear from the following description and claims.

In the annexed drawings, Figure 1 is an end elevation of a portion of a straight-knitting machine embodying my improvement. Fig. 2 is a partial plan thereof, certain parts being in section. Fig. 3 is a transverse vertical section, as on the line $\alpha\alpha$ of Fig. 2. Fig. 4 is an elevation of the yarn-carriers and adjuncts. Fig. 5 is a detail of the cam-bars, showing the coacting latch-arm in cross-section. Fig. 6 is a transverse horizontal section of the thread-carrier used in the knitting of the heel and toe parts of a stocking. Fig. 7 is a similar section of the carrier used in the knitting of the foot and leg portions. Fig. 8 is a view of the right-hand end stop with which the rack-bars coact.

B B are the oppositely-inclined needle-beds, and g the needles therein.

C is one of the reciprocating cam-carriages, C' the knitting-cams in said carriages, and D

the yoke which connects the same with the other carriage. (Not shown.)

M is one of the pattern-chains, which are disposed below the respective needle-beds and supported upon and intermittently rotated by appropriate wheels M' in the usual and well-known manner. The spring-actuated bits g' , which are connected with the lower or free ends of the vibratory needle-supporting jacks g^2 , bear yieldingly upon the links of the underlying pattern-chain, so as to be controlled thereby in a manner to elevate the needles at a certain time into the track of the knitting-cams and maintain them thus elevated for a given period or to permit the needles or some of them to be depressed below such cams at another time and for another period. Each of the chains is provided with a certain number of plain links, upon which bear the spring-actuated bits when the needles are in action, and each of the chains is also provided with links having therein relatively-located depressions with which said bits register to effect the depression and inaction of the needles. Only one of the chains and one row of needles are indicated in the drawings, as each side of the machine, with its needles and complementary parts, is a duplicate of the other.

It is well known that in the type of straight-knitting machines herein considered both sets of needles are simultaneously in action during the knitting operation not only during the production of tubular work, but during the knitting of fashioned work, the number of active needles of each set during the latter operation being of course decreased and increased at predetermined intervals.

E is a bar sustained above and parallel with the rear needle-bed by means of brackets E', rising from the ends of the main frame. In the Esty machine there is fitted and guided on this bar a carrier provided with an overhanging ledge, in which is supported a partially-rotatable spindle which depends directly above the throat of the machine and carries on its lower end a head provided with two relatively-arranged thread-guiding eyes. The spindle is provided with a pinion, with the respective sides of which engage toothed rack-bars arranged in the carrier, to the end

that when either bar is longitudinally moved the spindle is partially rotated in a manner to reverse the positions of the yarn-guiding eyes.

5 In pursuance of my invention I mount upon the bar E two thread-carriers H and H', which are rendered active and inactive in alternate succession—that is, during the knitting of the foot and leg of the stocking the 10 carrier H is in action while the carrier H' is inactive, and conversely. Two racks 11 contact with the pinion on the spindle I of the carrier H', which racks when said carrier is in operation are actuated at predetermined 15 periods by movable stops *i i* at the respective ends of the machine, the operation being identical with that of the carrier in the Esty machine during the formation of the toe and heel parts of the stocking. The rack-bars 11 20 are provided with extensions 22, which laterally embrace the carrier H', to the end that said extensions will in the traverse of the carrier H' clear the other thread-carrier H. The latter carrier is provided with a single 25 rack-bar 3, which in each stroke of the carrier is shifted endwise. In one stroke the end of the rack-bar abuts against the opposing stop *i*, while in the return stroke a lateral projection 4 on the bar abuts against a permanent stop 5 on the side of the main frame. 30 No removal or adjustment of the stop 5 is required, as during the knitting of the foot and leg the reversal of the thread-guides takes place at the end of each stroke of the carrier. 35 The stops *i i* are moved into and out of action in respect to the rack-bars similarly to the like stops in the Esty machine referred to, as follows: The stops are supported upon horizontally-movable rack-bars P, fitted to 40 bearings on the bar E and coacting with relatively-arranged spur-wheels Q. The hubs of the latter are provided with pinions R, with which engage segmental gears on the upper arms of rocking levers S, which are fulcrumed 45 upon the end brackets. The lower arm of each of these levers is provided with a tooth *k*, which rests upon an intermittently-movable chain T, the links of which are appropriately shaped to insure the actuation of the 50 lever and requisite adjustment of the stops. In the present construction the right-hand end stop against which the spindle-actuating rack-bars abut is provided with a bearing-piece *i'* of sufficient length to receive the impact of the widely-separated rack-bars 11. 55 The stud-shafts 6, which carry the levers S, are extended inwardly of the end brackets and are provided with forwardly-extending rock-frames 7, each of which carries on its 60 inner end a horizontal bar 8, whose lower edge is interrupted by a suitably-located offset or cam portion 9. The two bars extend from the transverse median line of the machine to the respective end heads, or nearly so, and are 65 independently movable through the action of their respective rock-shafts.

Pivoted to lugs 10 on the rear cam-carriage

C is a latch-arm 11, which extends upwardly against or near to the lower edges of the cam-bars 8, being yieldingly supported by the action of an underlying spring 12, which is affixed to the cam-carriage, to the end that when either of the bars is lowered the cam portion 9 thereof will depress the free end of the latch-arm coacting therewith.

70

Each of the thread-carriers is provided on its lower edge with a recess 13, with which the end of the latch-arm is adapted to be engaged when it is desired to reciprocate the carrier. When the latch-arm is engaged with one of the carriers, that carrier only is reciprocated by the cam-carriage, the other thread-carrier remaining quiescent at one end of the machine. At a prescribed time in the knitting operation one of the cam-bars 8 is depressed through the instrumentality of an appropriate link on the adjacent chain T, the lower edge of the bar thus depressing the latch-arm and disengaging it from the carrier as the latter reaches the end of its stroke. 80 The carrier thus released remains at the end of the machine, and the cam-carriage in its succeeding traverse is free from the thread-carrier, no thread in that event being delivered to the needles. The latch-arm at a predetermined period engages the recessed edge 85 of the thread-carrier lying at the opposite end of the machine and in the succeeding strokes impels the engaged carrier back and forth. When it is desired again to change the thread, 90 the proper cam-bar is depressed and the latch-arm thereby disengaged from the thread-carrier. The carrier is thus left at its end of the machine, and the latch-arm in a succeeding stroke reengages the thread-carrier at the 95 opposite end of the machine. In this way the thread-carriers are thrown into and out of action at certain intervals, as the requirements of the work may demand.

95

It will be seen that the two thread-carriers travel absolutely in the same path, that they are liberated at opposite ends of the machine, and that during their engagement by and disengagement from the latch-arm their stations must remain unchanged. It will also be seen 110 that the thread-carrier in operation will abut against the idle carrier and advance the latter beyond the normal position of engagement and disengagement. A spring-actuated abutment for the idle carrier is therefore provided, which abutment serves normally to return such carrier to the proper position. There is an abutment at each end of the machine, the same comprising a sleeve 14, loosely fitted on a fixed rod 15 and pressed normally 115 inward by a spring 16, which, encircling the rod, bears against the sleeve and an end bracket 17, by which the rod is supported. This rod lies adjacent to and parallel with the bar E, upon which the carriers slide. 120 Each carrier is provided on its upper side with a tappet-stud 18, which abuts against the opposing sleeve. 125

Inasmuch as the carrier H, which delivers

the yarn to the needles in the knitting of the foot and leg parts of the stocking, is in operation for a comparatively-long space of time it is desirable to lock the other carrier H' in the advanced position until it is required to return the same to its normal station for engagement by the latch-arm on the cam-carriage, as otherwise a prolonged seesawing of the idle carrier H' , with its threads, would be occasioned by the rapidly-recurring strokes of the active carrier. To this end I fulcrum on the end bracket adjacent to the station of the carrier H' a latch-lever 19, one arm of which overhangs the rod 15 and is held normally in the path of the abutment-sleeve by means of a suitably-disposed spring 20. The inner side of the sleeve is beveled or tapered; as at 21, so that when it is advanced by the movement of the idle carrier the sleeve will pass under and raise the lever-arm, which latter, dropping in front of the sleeve, will lock the sleeve in the retracted position. Preparatory to the reengagement of this carrier with the latch-arm on the cam-carriage the latch-lever 19 is raised to release the sleeve, which latter, together with the thread-carrier, is thereupon returned to its normal position by the recoil of the spring.

As a simple and efficient means to actuate the latch-lever at the proper time, I fulcrum loosely on the adjacent shaft 6 a lever 22, one arm of which rests upon the underlying pattern-chain T , while the other arm is provided with a laterally-projecting stud 24, which rests upon the outer arm of the latch-lever. One of the links of the chain T is provided with an appropriate riser, which at the proper time rides under the lever-arm and effects thereby the release of the latch-lever.

It will be obvious that locking devices of the character above described may be used in connection with the carrier H as well as the carrier H' . In fact, where the yarn is weak it will be advisable to provide for the locking of each carrier when it is not in operation.

In the drawings the levers and chains are illustrated in the positions they occupy just prior to the completion of the leg of the stocking, at which stage the substitution of one thread-carrier for the other is effected. As in this operation the chains are impelled only while the cams are moving from the left to the right hand side of the machine, it is necessary that the latch-arm make three idle strokes, the first of which is from right to left in order that at the proper interval said arm may be connected with the carrier. During these idle strokes all the needles are quiescent, the same being disengaged from the knitting-cams in the usual way through appropriate depressions in the pattern-chains. It will be seen that the teeth or riders k on the levers S occupy the same positions relative to the risers t on the links t' of the chains T and that the lever 22 lies adjacent to the riser on the link of the left-hand chain. It will also be seen that the riser on the right-

hand chain is double the length of that on the other chain. Now in one step of the chains the riser t on the left-hand chain rides under the lever 22 and effects the release of the locked thread-carrier H' , whereupon said carrier is moved to its normal position by the action of the spring 16 in order that at the proper time the latch may be engaged with said carrier. In the next succeeding step of the chains the teeth or riders k mount the risers t on the respective chains, thereby disengaging the latch-arm from the carrier H at the right-hand side of the machine, which arm, thus freed, makes an idle reciprocation—that is, from right to left and return. In the next following stroke to the left the riders remain elevated upon the risers t of the respective chains, and thus prevent the engagement of the latch-arm with the carrier H' . In the return stroke—that is, from left to right—the riser on the link of the left-hand chain escapes the rider k , whereupon the corresponding cam-bar 8 is raised, thus permitting the engagement of the latch-arm with the carrier H' in the succeeding stroke to the left. During the operation just explained the other cam-bar 8 remains in its down position by reason of the riser on the right-hand chain being double the length of the other riser, thereby preventing the engagement of the latch-arm with the carrier H at the end of the idle stroke to the right.

Excepting as above specifically stated, the pattern-chains are the same in construction and operation as the chains in the Esty machine referred to, and they therefore need no further description herein.

I claim as my invention—

1. In a straight-knitting machine wherein both sets of knitting-needles are simultaneously in action during the knitting operation, the combination with two oppositely-disposed rows of needles, knitting-cams therefor, and pattern mechanism for rendering said needles active or inactive in respect to the knitting-cams, of two independent thread-carriers movable in the same longitudinal path and including each a partially-rotatable spindle provided with two thread-guiding eyes, means for guiding said carriers, means for actuating the same, and means whereby said carriers are independently released and engaged at opposite ends of the machine together with means for partially rotating the spindle of each carrier at predetermined intervals.

2. In a straight-knitting machine wherein both sets of knitting-needles are simultaneously in action during the knitting operation, the combination with two oppositely-disposed rows of needles, knitting-cams therefor, and pattern mechanism for rendering said needles active or inactive in respect to the knitting-cams, of two independent thread-carriers movable in the same longitudinal path and including each a partially-rotatable spindle provided with two thread-guiding

4 eyes, means for guiding said carriers, a movable latch-arm on one of the cam-carriers, and means whereby said arm is independently engaged with and disengaged from said thread-carriers at opposite ends of the machine, together with means for partially rotating the spindle of each carrier at predetermined intervals.

3. In a straight-knitting machine of the character described, the combination with the needle-bed, needles and cam-carrier, of a plurality of independent thread-carriers, means for guiding the same longitudinally of the machine, a movable latch-arm on the cam-carrier adapted to engage and disengage said thread-carriers at predetermined intervals, at opposite ends of the machine, cam-bars movable into and out of the path of said latch-arm, supports for said bars, and means whereby said supports are independently actuated.

4. In a knitting-machine of the character described, the combination with the needle-bed, needles, and cam-carrier, of two independent thread-carriers, means for guiding the same longitudinally of the machine, a movable latch-arm on the cam-carrier, adapted to engage and disengage said thread-carriers at predetermined intervals, cam-bars movable into and out of the path of said latch-arm, rock-frames supporting said bars, shafts for said frames, pattern mechanism, and independent connections between the same and said shafts.

5. In a straight-knitting machine wherein both sets of knitting-needles are simultaneously in action during the knitting operation, the combination with two oppositely-disposed rows of needles, knitting-cams therefor, and pattern mechanism, for rendering said needles active or inactive in respect to the knitting-cams, of two independent thread-carriers movable in the same longitudinal path, means for guiding said carriers, means for actuating the same, yielding abutments for said thread-carriers, and means whereby the latter carriers are independently released and engaged at opposite ends of the machine.

6. In a knitting-machine of the character described, the combination with the needle-bed, needles and cam-carriage, of two independent thread-carriers movable in the same longitudinal path, means for guiding said carriers, means for actuating the same, yielding abutments for said carriers, means whereby the idle carrier is locked against the action

of its abutment, and means whereby the said carriers are independently released and engaged at opposite ends of the machine.

7. In a knitting-machine of the character described, the combination with the needle-bed, needles and cam-carriage, of two independent thread-carriers, means for guiding the same, means whereby said carriers are independently released and engaged at opposite ends of the machine, spring-actuated abutments for said carriers, a latch-lever adapted to automatically engage and lock the idle carrier against the action of its abutment, pattern mechanism, and connections between the same and the latch-lever.

8. In a knitting-machine of the character described, the combination with the needle-bed, needles and cam-carrier, of two independent thread-carriers, means for guiding the same longitudinally of the machine, a movable latch-arm on said carrier, adapted to engage and disengage said thread-carriers at predetermined intervals, cam-bars movable into and out of the path of said latch-arm, rock-frames supporting said bars, shafts for said frames, pattern mechanism, independent connections between the same and said shafts, spring-actuated abutments for said carriers, a latch-lever adapted to automatically engage and lock the idle carrier against the action of its abutment, and connections between the pattern mechanism and said latch-lever.

9. In a knitting-machine of the character described, the combination with the needle-beds, needles and cam-carriages, of two independent thread-carriers H, H', whereof each includes a partially-rotatable spindle having a pinion and duplex thread-guide, the carrier H' being provided with two racks 1 having extensions 2, and the carrier H being provided with a single rack, stops with which said racks coact means for supporting and operating said stops at predetermined intervals, means for guiding said carriers, means for actuating them, and means whereby said carriers are independently released and engaged at opposite ends of the machine.

In testimony whereof I affix my signature in presence of two witnesses.

JOSEPH NELSON BENNOR.
